(No Model.)

C. C. BURTON.

CAR COUPLING.

No. 328,458.

Patented Oct. 20, 1885.

UNITED STATES PATENT OFFICE.

CHARLES COE BURTON, OF SAMARIA, MICHIGAN, ASSIGNOR OF ONE-HALF
TO ARTHUR L. HOLDEN, OF UTICA, NEW YORK.

CAR-COUPING.

SPECIFICATION forming part of Letters Patent No. 328,458, dated October 20, 1885.

Application filed April 21, 1884. Serial No. 128,658. (No model.)

To all whom it may concern:

Be it known that I, CHARLES COE BURTON, of the village of Samaria, in the county of Monroe, in the State of Michigan, formerly in allegiance to the Queen of Great Britain and a subject thereof, but who came to the United States in the year 1875 and have ever since resided therein, and since 1877 have resided in the State of Michigan, and on February 23, 1884, made my declaration of intention to become a citizen of the United States, in the circuit court for the county of Monroe, in the State of Michigan, have invented a new and useful Improvement in Car-Couplings; and I do hereby declare the following to be a full, clear, and exact description of the same, reference being had to the accompanying drawings, and to the letters and figures marked thereon.

My invention relates to a novel and simple method of coupling and uncoupling cars by means of a swinging double-prong coupling-pin pivoted in the opening of a draw-head and forming an inclined plane on which the drag-link is raised, in combination with a movable clutch-link and other suitable means for rotating the same, as hereinafter described.

In the accompanying drawings, Figure 1 represents a section of the side of a car with my improved coupling attached. Fig. 2 represents a plane view of a horizontal section of my improved draw-head catch, taken at X X in Fig. 1. Fig. 3 represents a top view of my improved draw-head catch and the link in place. Fig. 4 represents a longitudinal sectional view of my improved draw-head with coupling-pin and clutch-link in place and engaged with a drag-link, also showing the inclined plane in dotted lines. Fig. 5 represents an end view of the draw-head pin and a cross-section of the coupling-link. Fig. 6 represents a side and end view of my improved coupling-pin. Fig. 7 represents a top view of my improved draw-head catch.

Having described my invention in reference to the figures marked on the accompanying drawings, I will now proceed to describe it by reference to the letters marked thereon, in which similar letters refer to corresponding parts throughout the several views.

A represents a section of the frame or sills of an ordinary freight or passenger car.

B represents my improved draw-head.

K represents an angular moving coupling-pin formed of wrought-iron or steel, and of the required size to stand the required strain. This pin has a large eye of sufficient size to receive a bolt of sufficient strength, with a strong eye-shank, the two projecting angles of sufficient size and strength to stand the required strain, and formed substantially as indicated in Figs. 4 and 6. This catch is pivoted in the open draw-head by means of bolt b passing through the sides of the draw-head. The inner portion of the head is cut away to admit the swinging pin and the link-coupling to be inserted.

When the car is to be coupled the approaching drag-link, coming in contact with the inclined plane formed by K² and rising thereon, strikes K' and drives it back. K² is thereby lifted and engages the drag-link. This link comes in contact with the upper side of the draw-head mouth, which, with K', then forms a wedge-shaped aperture. The drag-link being driven therein forces K' down and K² is thereby engaged with the catch-link. The circular end of K² striking the catch-link lifts the same and passes under the catch, which falls by its own weight over the end of the coupling-pin K², thereby coupling the cars. To uncouple the same, the operator can step to the side of the car and raise crank-arm c, and thereby uncouple the car.

R represents the coupling-catch, constructed of a strong rod of iron or steel of the required size, which passes nearly or quite the width of the car, with a V-shaped loop in the middle, one strong bearing each side of the V-shaped loop and strongly secured to the draw-head by staples S S, and the outer ends pivoted in the ends of the braces b² and b², so attached to the car-sill as to move with the draw-head with the spring attachment S'.

C C represent cranks on the end of the catch-arms.

U represents the loop-catch. Attached to the loop U is a chain to operate the device from the top of an ordinary box-car.

C' represents the chain.

S^4 represents a longitudinal slot in the upper surface of the draw-head, to receive and support the **U**-shaped loop or clutch-link, and S^5 represents a longitudinal slot in the lower 5 part of the draw-head.

What I claim as new, and desire to secure by Letters Patent, is—

1. In a car-coupling, the combination, with the draw-head having a **V**-shaped mouth and 10 a longitudinal slot in its upper side and a corresponding groove or recess in the lower side, in which is, at the front of the draw-head, a double-prong coupling-pin resembling the letters **V** or **L**, and being pivoted at its angle,

15 the long arm of the letter forming the coupling-pin and extending beyond and below the face of the draw-head, forming an inclined plane or apron upon which the drag-link is raised to enter the mouth of the draw-head, 20 substantially as described and for the purpose set forth.

2. In a car-coupling, the combination, with a draw-head having a longitudinal slot in its upper side and a groove or recess in the lower 25 side having a double coupling-pin pivoted in the front of the draw-head and forming an inclined plane or apron, as described, of a clutch-link pivoted on the top and back of a draw-

head with its engaging end turned forward and falling over the point of the coupling-pin 30 K^2 when the same is engaged with the drag-link, the point of the pin and the end of the catch-link being formed on a bevel, forming a latch, substantially as described.

3. In a car-coupling, the combination, with 35 a clutch or catch link pivoted on the top of a draw-head and having the operating-rod and weighted hand-levers with the small eye for lifting-chain, all wrought in one for the purpose of maintaining the clutch-link in its seat, 40 provided with suitable means for rotating the catch or clutch, substantially as described.

4. In a car-coupling, the double-prong movable coupling-pin pivoted at its lower end and forming an inclined plane, in combination 45 with a draw-head and bumper, the double-prong coupling-pin pivoted at its lower end and engaging a drag-link between its prongs and at the same time engaging itself with a clutch-link, substantially as described.

Signed this 15th day of April, 1884.

CHARLES COE BURTON.
